STITCHING MECHANISM FOR JOINING
CORDS OR THE LIKE WITH A FABRIC

Louis Brumberger, New Haven, Conn., assignor
to Mercury Sportswear, Inc., New Haven, Conn.,
a corporation of Connecticut

Application March 22, 1950, Serial No. 151,160

1 Claim. (Cl. 112—100)

1

The present invention relates to stitching mechanism, and, more particularly, to stitching mechanism or devices for joining or attaching a cord, such as an elastic cord or tape, to a fabric. The fabric may be cloth from which a dress or bathing suit is to be formed.

In accordance with the present invention, means are provided for causing a stitching thread or threads to be laid successively on alternate sides of a cord, elastic strand, tape, or the like. The invention contemplates service of one or more cords into the stitching area. Service of two cords is shown by way of example in the accompanying drawing, but it will be understood that any desired number of cords may be served to the stitching area. Devices constructed in accordance with the invention may be operated in a manner to produce a so-called ruffled fabric when tension on the cord or cords is released after removal from the stitching area. It will be understood that the cord may pass into the stitching area without being maintained under substantial tension. The invention contemplates an attachment which can be applied to either a single or multiple needle lock-stitch sewing machine. The fabric passing through the stitching area of the sewing machine is moved forwardly with respect to the stitching operation. The cord or strands are fed with an oscillatory motion correlated with the movement of the fabric to which the cords are to be attached. The usual lock-stitch is preferably employed to secure the cord or cords against one face of the fabric.

The primary object of the present invention is to join or attach a cord or cords to a fabric in a novel manner.

Another object is to provide novel apparatus for cooperation with the stitching mechanism of a sewing machine to secure a strand such, for example, as an elastic cord on the face of a piece of cloth.

A further object is to provide a novel apparatus for use with the stitching mechanism of a sewing machine for securing a cord against the face of a piece of cloth.

A still further object is to provide novel means for securing a cord or tape against the surface of a fabric without piercing the cord or tape.

Other objects and advantages of the present invention will, of course, become apparent and immediately suggest themselves to those skilled in the art to which the invention is directed from a reading of the following specification in connection with the accompanying drawings in which:

Fig. 1 is a view in perspective of a portion of the head of a sewing machine equipped with cord

2

securing apparatus in accordance with the invention;

Fig. 2 is a fragmentary view in front elevation of the machine illustrated in Fig. 1;

Fig. 3 is a fragmentary view in side or end elevation of the machine of Fig. 1;

Fig. 4 is a plan view in section, the section being taken on line 4—4 of Fig. 3;

Fig. 5 is a fragmentary view in plan similar to Fig. 4 but showing the parts in another relative position; and

Fig. 6 is a view in plan of a piece of fabric provided with attached cords in accordance with the invention, this view being illustrative of either nonstretchable cords with the fabric and cords as a finished product, or fabric with stretchable cords prior to release of tension on the cords to provide a ruffled fabric.

Referring to the accompanying drawing, reference character 10 designates the entire head of a sewing machine of a known kind. A showing of the usual and well known sewing mechanism of the machine is omitted for the sake of convenience of description and clearness of disclosure.

The sewing machine chosen as an illustrative setting of the invention is of the "lock-stitch" type having the usual bobbin and shuttle mechanism with the accompanying thread tension and feeding devices (not shown).

The machine head 10 includes an arm 12, shown fragmentarily, which houses the reciprocating mechanism for the needle bar 14. A flywheel 16, which serves also as a handwheel, is mounted on a shaft 18. This shaft serves to impart co-ordinated motion to the needle bar 14, the cloth feeder 21, and the thread feeding mechanism (not shown) for the needle or needles and the bobbin. The cloth feeder 21 advances or assists in advancing, a fabric piece through the area in which the sewing needle operates. The wheel 16

may be driven by any suitable means, such, for example, as a motor pulley or a belt. The cloth feeder 21 moves the fabric or goods 23 along the sewing table 25 of the sewing machine head 10 by its usual reciprocating movement. This movement of the feeder 21 is toward the left, as viewed in Fig. 3 and it is retracted for the return stroke.

The arm 12 is provided with a presser foot bar 27 which is raised or lowered by a hand lever 29. The latter is usual equipment on a sewing machine. The presser foot bar 27 carries an attachment 31 which is constructed in accordance with the present invention. The attachment 31 comprises a stationary member 33 and a reciprocating member 36. The latter is carried by and secured to a yoke 38 which is fastened to a rod 39.

The member 36 has clearance openings 40 and 41 to accommodate the sewing needles 66 and 67. Suitable means, such as screws 42, serve to secure the member 36 to the yoke 38. Screws 44, for example, secure the yoke 38 to the rod 39. The rod 39 is free to reciprocate in holes in the arms 46 to a bearing member 48. Both the stationary member 33 and the bearing member 48 are suitably secured to the presser foot bar 27.

Reciprocating movement is imparted to the rod 39 and hence the member 36 by means of a connecting rod 51 which is pivotally connected to a stub shaft 52 projecting from the rod 39. The other end of the rod 51 is pivotally connected to a crank or eccentric device 54. The eccentric 54 is continuously driven from the main shaft 18 through suitably meshing gears 56 and 57, the latter being secured to the eccentric shaft 61. It will be understood by those familiar with or skilled in the sewing machine art that the movements of the needle bar 14, and rod 39, and the thread bobbin mechanism (not shown) will be coordinated since they are connected mechanically to the main shaft 18 of the sewing machine.

The stationary member 33 is provided with holes 63 and 64, one for each sewing needle 66 and 67.

Sewing threads 71 and 72 are fed to the sewing needles 66 and 67 in any manner usual in the sewing machine art. These threads are tensioned as usual and pass from reciprocating take-ups, or the like (not shown). The needles pass through the holes 63 and 64 as they reciprocate into the sewing table or sole plate 25.

Cords or strands 76 and 77, which may be elastic cords, are fed from suitable skeins, reels or spools (not shown) to holes 78 and 79 pierced from the end of the reciprocating member 36. The cords 76 and 77 pass through the needle openings 63 and 64 to the fabric 23. The holes 78 and 79 receive the strands and permit feeding of the strands onto a fabric piece advancing through the area in which the stitching needle operates. As will be seen from Figs. 4 and 5, the movement of the reciprocating member 36 carrying the cords 76 and 77 will feed the cords from one side of the needles to the other causing the needles to form a stitch 80 beginning on one side of the cords and finishing on the other side as shown by Fig. 6.

It will be observed that each cord or strand is centered in the end of the hole 63 or 64 beyond the operating point or zone of the needle. It will also be observed that the fabric or goods 23 moves substantially in a straight line as is usual with sewing machines. This is a distinct advantage since it permits usual and well developed sewing machine procedures to be followed. The strand or cord, however many in number, is or are oscillated at a coordinated rate as they are fed to the sewing area or zone. In accordance with the invention, this is readily arranged.

If the so-called ruffled fabric, popular for bathing wear, is to be produced in accordance with the invention, the cords 76 and 77 will be of elastic material. They are then preferably fed under tension maintaining means (not shown) to the holes 78 and 79, tension being maintained by a frictionally controlled feed or by a speed coordinated feed. A cord feed which is timed to be slow with respect to feed of the fabric 23 through the stitching area will accomplish this result when desired. A pair of rollers 83 and 84 serves to draw the fabric completed in accord-

ance with the invention, from the sewing area in the region of the needle or needles 66 and 67. Where the produced fabric is to be ruffled, the roller, or rollers 83 and 84, are driven at a speed to maintain tension and stretch in the cord or cords 76 and 77. When the tension and stretch are relieved, the fabric assumes the aspect indicated by reference character 88 applied to Fig. 1. It will be understood that it is within the scope of the invention to time rotation of the roller 84 or the rollers 83 and 84 merely to draw the completed fabrics 23 from the sewing area. In the latter case, the fabric will not "ruffle" irrespective of whether or not the strands 76, 77 and perhaps others are made of elastic material.

It will be understood that either one of the rollers 83, or 84, or both, may be driven for rotation by suitable mechanical means (not shown) coordinated with the angular velocity or speed of rotation of the main shaft 18 of the sewing machine including mechanism in accordance with the present invention.

Conventional bearings and supports 91 and 92 are shown for the rollers 83 and 84. It will be understood that the roller 83 or the roller 84 may be electrically driven separately from the mechanism of the sewing machine. Since means adapted for doing this are well known, they are not shown separately. If electrical means are employed as suggested herein, they may be controlled as to speed of rotation. This may be accomplished by utilizing electrical synchronization as, for example, a synchronous motor.

The invention claimed is:

35 Mechanism for securing a strand against the surface of a fabric piece comprising: a stitching needle, means to cause said needle to reciprocate to execute successive stitching strokes, feed means to advance a fabric piece longitudinally through the area in which said needle operates, 40 a presser member having an elongated strand guiding opening to receive the needle, said presser member being positioned above said feed means, means to cause movement of said presser member vertically to release a fabric piece, an apertured plate superimposed above said presser member, means to cause vertical movement of said plate with said member, said plate having a longitudinal opening in advance of said guide opening in said presser member and being superimposed to overlap said presser member to receive a strand and to permit feeding of the strand onto an advancing fabric piece through said opening in said presser member, and timed 45 means to horizontally reciprocate said plate and the longitudinal opening therein with respect to each successive stitching stroke of said needle and an advancing fabric piece whereby said strand is fed alternately on opposite sides of said operating needle, the opening in said presser member being of a width to limit feeding of said strand laterally.

LOUIS BRUMBERGER.
